(57) **CLAIM**

(22) Filed: **Jun. 28, 2005**

The ornamental design for a modular electronic housing and assemblies, as shown and described.

Related U.S. Application Data

DESCRIPTION

(62) Division of application No. 29/195,922, filed on Dec. 8, 2003, now Pat. No. Des. 499,567.

The modular electronic housing and assemblies comprises a modular electronic housing intended to be used to house electronic circuit boards and their included electronic components.

(51) **LOC (8) Cl.** 13-03

The FIGURE is a right side perspective view of a modular electronic housing and assemblies showing our new design.

(52) **U.S. Cl.** **D13/184**

The broken line disclosure in the drawings are for illustrative purposes only and form no part of the claimed design.
